CLAIM

The ornamental design for a can, as shown and described.

DESCRIPTION

FIG. 1 is a perspective view of a can showing our new design;

FIG. 2 is a front elevational view thereof, the rear elevational view is the same;

FIG. 3 is a side elevational view thereof, the opposite side is the same;

FIG. 4 is a cross sectional view taken on the line 4—4 of FIG. 2;

FIG. 5 is a bottom view thereof; and,

FIG. 6 is a vertical cross-section of the can, shown in FIG. 1.

The characteristic feature of our design resides in the specific configuration of the fluting pattern in combination with the can.
